[57] CLAIM

The ornamental design for a peak flow meter, as shown and described.

DESCRIPTION

FIG. 1 is a top, front and left side perspective view of a peak flow meter showing my new design;
FIG. 2 is a bottom, rear and right side perspective view;
FIG. 3 is a left side elevational view, the right side elevational view being identical thereto; and,
FIG. 4 is an inverted front elevational view thereof.
FIG. 4 has been drawn on a reduced scale with respect to FIGS. 1-3.

*Fig. 1**Fig. 2**Fig. 3**Fig. 4*
